Des. 83

D. F. Goodhue, & Charles Gild, Cincinnati, Ohio.
Letters Patent (Design No. 83) dated 18th. August 1846.

The Schedule referred to in these letters patent
and making part of the same

To all whom it may concern:

Be it known that

we, D. F. Goodhue and Charles Gild of the City of Cincinnati in
the State of Ohio, have invented and produced a new and useful
Design for the ornamenting ^{and} a new and useful shape or configu-
ration, of a stove for heating apartments; and we do hereby declare
that the following is a full and exact description thereof:

The particular shape or configuration of our stove with
the respective ornaments thereon, are shown in the accompanying
drawings, in which fig. 1 is an elevation of the front, fig. 2 an eleva-
tion of one end, and fig. 3 a plan of the top plate and of the health,
or bottom plate thereof. The outline of the front and end elevations,

and of the hearth plate will sufficiently distinguish the particular shape or configuration of our stove. The front plate A which extends from the top plate B, down to the hearth plate C, has the ornamental devices upon it that are shown in fig. 1. There are on this plate two ornamental pannels a a containing an eagle surrounded by a wreath, and below and above this eagle the ornamental scrolls, leafing and flowers shown in the drawing.

The sides of these pannels are bounded by a carved moulding such as is shown at b b; an ornamented revolving register c c occupies a part of the space between the pannels as represented; and above and below this, between the said pannels are the other ornamental designs which we use. Below the pannels is the ornamental scroll-work d d and the curved border e e. Below the border e e is the moulding part f f and g g; this moulding part consists of open fret work through which air is admitted to the fire; the parts h h constitute the openings the fret work being ornamented as represented. The edges of the front plate have an ornamental border e e which is similar to that so marked below the scroll-work d d. Between the borders b b and e e on the sides of the pannels is the ornamental leafing and flower work i i. The upper part D D of the front plate, which may be considered as forming a portion of its cornice, has on it the ornamental leafing j j.

E E is the top plate of the stove which is shown in plan in fig. 3. This has on it the two ornamental leafwork mouldings K K & L L. (figs 1 & 3) F shows the collar for the exit pipe. The top plate is surrounded by an open fret work gallery G G, having on it two griffins and the respective ornaments as represented thereon.

The back plate of the stove is the same in shape or configuration with the front plate, the two pannels a a with their ornaments are also the same, but the register c c is omitted and we also in general omit a part of the ornaments, the parts omitted being the ornamental work between the pannels, the scroll-work d d under them and the flower work i i.

shown in fig. 1. All these however may be included when the stove is intended to stand in a situation where all its sides are fully exposed to view.

In the drawing of the end elevation fig. 2 all the ornaments are unrepresented excepting where they differ in certain particular form. Those used on the front plate. The panel a a is single but its ornaments are precisely the same with those in fig. 1; its cornice moulding or border b b is also the same as well as the border c c and the flower work i i. The moulding D D at the top is a continuation of that so marked on fig 1. The ornaments on the top plate are also the same. The scroll work d d varies slightly it will be seen from that marked dd in fig. 1; and also its contraction in width has induced a variation of form in the open fret work under the panel as shown at ff g g'. The open fret work forming the end of the gallery is ornamented in the manner shown at cc'.

The bottom or hearth plate c fig. 3 has the configuration represented in that figure; and it has on it the respective scrolls, leafing, and other ornaments constituting its border as shown at m m m, within this border is the ornamental moulding n n against which the plates forming the front, back, and sides of the stove, bear.

Having thus fully described and represented the shape or configuration of our stove, and the various ornaments devised by us to embellish the same, what we claim therein as new and desire to secure by Letters Patent, is, first, the particular shape or configuration of the stove as a whole; we claim the manner represented of ornamenting the front, back and end plates thereof, with such variations therein as we have designated; we claim the configuration of, and ornaments upon, the bottom or hearth plate as represented; we claim the top plate having on it its two courses of ornamental mouldings as represented; and we also claim the front and end plates of the open fret work gallery as represented.
